UNITED STATES PATENT OFFICE.

JOHN W. SPURLOCK, OF FOLKSTON, GEORGIA

WOOD-DISTILLING APPARATUS.

1,190,478.

Specification of Letters Patent. Patented July 11, 1916.

Application filed February 25, 1916. Serial No. 80,496.

To all whom it may concern:

Be it known that I, JOHN W. SPURLOCK, a citizen of the United States, residing at Folkston, in the county of Charlton and State of Georgia, have invented new and useful Improvements in Wood-Distilling Apparatus, of which the following is a specification.

This invention relates to a wood distilling apparatus, designed for the distillation of pine woods in the production of turpentine, pine oil, tar and charcoal, and the separation of the distillates from each other.

The primary object of the invention is to provide an apparatus for treating wood by the process of destructive distillation, and which is of a type to efficiently perform the distilling condensing and separating operations in a reliable and efficient manner, at a comparatively low cost for fuel and without material loss of the lighter vapors from overheating or of undue admixture of the turpentine and pine oil.

A further object of the invention is to provide a distilling apparatus, embodying an inclosing casing and two or more distilling kilns or chambers arranged therein, and provided with flues and chimneys for the most efficient application and use of all of the available units of heat and the discharge of the products in a manner to reduce liability of overheating, the kiln chambers being of a construction to admit of the same being readily, conveniently and inexpensively built up of portable sections of sheet metal, so that the erection of kilns at more or less remote points may be inexpensively carried out.

The invention consists of the features of construction, combination and arrangement of parts herein fully described and claimed, reference being had to the accompanying drawings in which:

Figure 1 is a front elevation of a wood distilling apparatus embodying my invention, showing an apparatus having duplicate kiln chambers. Fig. 2 is a sectional plan view of the same. Fig. 3 is a sectional side elevation taken substantially on the line 3—3 of Fig. 2. Fig. 4 is a vertical longitudinal section on the line 4—4 of Fig. 2. Fig. 5 is a vertical transverse section on the line 5—5

of Fig. 2. Fig. 6 is a horizontal longitudinal section, on an enlarged scale, through one of the kiln walls.

Referring to the drawings, showing the application of my invention to a distilling apparatus embodying two distilling chambers or kilns, 1 designates an outer inclosing casing, made of plain brick, fire brick, cement, metal or other suitable material, and which is of rectangular or oblong rectangular form and provided with a top or roof 2, preferably made of reinforced concrete, which top or roof also serves as the top or roof of a pair of duplicate kilns or distilling chambers 3 arranged within said inclining casing.

The kiln chambers 3 are each formed of side walls 4 and a rear end wall 5, said kiln chamber being open at the front and closed at the top by the cover 2, and resting at its base upon a bottom 6, which also forms the bottom or floor of the outer furnace chamber or casing 1 and the contained parts of the apparatus as an entirety. The portions of this floor forming the bottom of each kiln chamber are provided with inclined surfaces 7 which slope from the sides of the chamber to a point midway of the length of the chamber 80 so as to form a central gutter or drain channel 8, for a purpose hereinafter described.

The wood to be treated is arranged in practice in stacks upon suitable wheeled trucks or cars which are run into the kiln chambers on central tracks 9, the open forward ends of the kiln chambers being closed, after having been charged, by suitable doors 10, of a construction to withstand and keep confined the contained heat. For the purpose of providing kiln chambers which may be conveniently constructed of portable sections, the walls of each chamber are formed of sheet metal plates 11 which are provided with marginal outturned flanges 12, between 95 which are placed metallic fillers 13 secured to the flanges of adjacent plates by bolts or rivets 14, said strips serving as reinforcing and packing elements. Where the outside casing or furnace casing is constructed of 100 brick or other materials which are easily procurable, the kiln chambers may be made of metallic sections as described with great convenience and economy, as the metal sec-

tions will be of a size to be easily made and transported by ordinary transportation facilities in command in districts where the distilling operations are to be carried out.

5 It will, of course, be understood that when desired the outer or furnace casing may be made also of metallic sections suitably insulated to prevent chilling of the furnace and loss of heat therefrom.

10 The kiln chambers are separated from each other and from the sides and rear ends of the casing 1 to provide an intervening vertical longitudinal flue 15 between the adjacent sides of the kilns, similar flues 16 be-

15 tween the outer sides of the kilns and the side walls of the casing, and transverse flues 17 connecting said longitudinal flues at the rear end of the apparatus, the arrangement being such that the heat supplied to the

20 furnace chamber may surround the kilns as fully as possible to utilize all of the available heat units to heat the interior thereof to the desired degree and to maintain the working temperature in an easy and uni-

25 form manner. At the ends of the furnace casing, and preferably upon the exterior thereof are furnaces or combustion chambers 18, designed to burn a suitable fuel and which are in communication through pas-

30 sages 19 with the internal flues for the flow of the products of combustion from said furnaces to the interior of the furnace casing, and around the kiln chambers, so that the interior of the kilns will be heated in an ob-

35 vious manner. The furnaces supplying the side flues are preferably arranged at one (the rear) end of the casing, while the furnace supplying the central flue is preferably arranged at the front of the casing, as shown,

40 but any other desired arrangement of the furnaces may be employed. The object of the above described arrangement of the furnaces is to secure a more uniform and equable distribution of the heat throughout the

45 area of the kiln. For the purpose of further and more efficiently securing an equable distribution of the heat, the flues are sub-divided by horizontal partitions 19' into upper and lower compartments, the upper

50 compartments being heated solely by radiation and conduction from the lower compartments, which are in direct communication with the furnaces at one end and with the flues at the opposite end, the flues ex-

55 tending downward through the upper compartments. This arrangement of the partitions prevents the overheating of the top portion of the kiln, and the more uniform heating of the lower portion of the kiln, the

60 storage of heat within the upper compartments furthermore obviating any liability of the kiln becoming chilled or subjected to rapid temperature changes. The opposite or forward ends of the flues communicate

65 with stacks or chimneys 20, through which

the products of combustion after circulating through the flues and heating the kiln chambers exhaust to the atmosphere.

As will be evident a portion of the gases from the side furnaces pass through flues 16 forward to the stacks 20, while a portion of the gases from the center furnace pass backward through the center flue 15 to a stack 20. Also it will be evident that the remainder of the gases not taking a direct course from the furnaces through the longitudinal flues to the stacks will commingle and flow through the various passages 17 before discharging through the stacks, thus securing a circulation throughout the entire area of the outer casing before discharging therefrom. The stacks open into the flues below the partition 19', which closes the space above said partition from the flues below thus preventing the gases from passing to the space above the partition. This space serves as an air chamber in which the air is heated from the flues through conduction and radiation, and which insulates the retort flues from the atmosphere to diminish liability of the chilling of the vapors.

The wood stacked upon the cars within the kiln chambers is subjected to a proper degree of heat to drive off the volatile constituents thereof for the production of turpentine, pine oil and tar, the residue being left in the form of charcoal of substantially uniform fine quality throughout. It will be understood that the lighter and heavier volatile constituents or vapors driven from the wood are liberated for discharge within the kiln chambers, while the tar drips down on to the floor or bottom surfaces of the chambers and down the sloping sides thereof into the gutters or channels 8. Arranged externally of the casing at opposite sides thereof are vats 21 and condensers 22, one vat and condenser for each distilling kiln employed, the vat being preferably embedded in the ground, while the condenser is preferably mounted at an elevation upon a supporting framework 23. The condenser may be of that type comprising an outer jacket or casing 24 and an inclosed worm or coil 25, kept cool by exposure to the air to the action of cooling water. In accordance with my invention, the products of the process of distillation all pass outwardly from each kiln chamber through discharge pipes 26, two of which pipes are preferably employed in connection with each kiln, leading from opposite sides of the transverse center of the kiln to the tar vat 21. The ends of the pipe extending into this vat are provided with depending tar discharge outlets 27 and vapor outlets 28, which latter connect with the vapor conducting pipes 29 leading to the inlet of the condensing coil, the tar flowing by gravity through the pipes 26 and outlets 27 into the tank 21, and the

vapors passing through the pipes 29 to the condenser for condensation into turpentine and pine oil, which are later separated by specific gravity or in any other preferred manner.

It will be observed that the evolved products are discharged from the bottom of each kiln, the kiln being closed at all other points against the discharge of the same, the result being that both the tar and the volatile constituents are kept at a proper temperature to prevent congealing of the tar or condensation of the volatile constituents within the kiln, and at the same time the volatile constituents of different specific gravities are kept in a condition for discharge and separation. As the vapors are compelled to flow downward for discharge, the contained heat is uniformly and evenly diffused throughout the kiln body, thus insuring a regular and even heating of the wood and its reduction to charcoal, while preventing excessive heating of the vapors and their consequent injury or destruction by the conversion into their component gases. Furthermore, a better grade of turpentine is produced than is possible with ordinary destructive distillation processes, involving outside heating, as a less intense heat is required for the driving off of the constituents of the wood, with less liability of the contamination of the vapors. By reason of the construction described and arrangement of kilns as set forth, economy of heat and fuel is insured in an obvious manner, and inasmuch as the sides and ends of the retort are constructed of steel expansion and contraction thereof is readily taken care of, so that the retort will retain its shape for a long period. The bottom and top of each retort is constructed of concrete in order to protect such portions of the kiln from the action of acids evolved from the wood. The tar deposited in the vat 21 is conducted therefrom into a settling tank 30, preferably through a steam siphon 31, from which tank the tar may be withdrawn for use when desired. Inasmuch as the vapors are all recovered from the wood and tar, by the process described, the necessity of treating the tar for the separation of other products therefrom

is avoided, with added convenience and economy.

I claim:

1. A wood distilling apparatus comprising an outer inclosing casing of oblong rectangular form, a plurality of distilling chambers of corresponding form arranged within said casing, said chambers being arranged on opposite sides of the longitudinal center of the casing and spaced from each other and from the side walls of the casing to provide intervening longitudinal flues, and also spaced at one end from the adjacent end wall of the casing to provide transverse flues connecting said longitudinal flues, the casing and distilling chambers being provided with doorways at the opposite end thereof, doors for closing said doorways, furnaces arranged at one end of the casing on opposite sides of the longitudinal center thereof and communicating with the outer side and transverse flues, a furnace arranged at the opposite end of the casing between the doors and communicating with the central flue, and stacks at the ends of the flues opposite the furnaces.

2. A wood distilling apparatus including an outer casing of oblong rectangular form, distilling chambers of corresponding form arranged within the outer casing on opposite sides of the longitudinal center thereof, said outer casing and distilling chambers having doorways at one end thereof, and said chambers being spaced at their opposite ends from the opposite end of the casing to provide transverse flues and also being spaced from each other and from the sides of the casing to provide longitudinal central and side flues, doors for closing said doorways, heaters communicating with the flues, stacks communicating with the flues, and horizontal longitudinal partitions separating the lower portions of the flues from the upper portions thereof.

In testimony whereof I affix my signature in presence of two witnesses.

JOHN W. SPURLOCK.
